UNITED STATES PATENT OFFICE.

CHARLES A. FEESER, OF MUNSON, WEST VIRGINIA.

FASTENING DEVICE.

SPECIFICATION forming part of Letters Patent No. 621,913, dated March 28, 1899.

Application filed October 27, 1898. Serial No. 694,680. (No model.)

To all whom it may concern:

Be it known that I, CHARLES A. FEESER, a citizen of the United States, residing at Munson, in the county of Morgan and State of West Virginia, have invented certain new and useful Improvements in Fastening Devices, of which the following is a full and complete specification, such as will enable those skilled in the art to which it appertains to make and use the same.

This invention relates to fastening devices; and the object thereof is to provide an improved device of this class which is designed to be connected with the back collar-button and with the vest, coat, or other garment, so as to prevent the neckband and collar from rising at the back of the neck.

The invention is fully disclosed in the following specification, of which the accompanying drawings form a part, in which—

Figure 1 is a front elevation of my improved fastening device; and Fig. 2, a side view thereof, showing the method of connecting the fastening device with the collar-button and coat, vest, or other garment.

In the drawings forming part of this specification the separate parts of my improvement are designated by the same numerals of reference in both views, and in the practice of my invention I provide a strap 5, which is preferably composed of elastic material and which is provided adjacent to each end with a link 6, having a longitudinal central cross-bar 7, and the strap 5 is connected with the links 6 by being passed therethrough and folded backwardly, so as to form loops 8, this form of construction being well known.

One end of the strap 5 is provided with a hook 9, composed of a back 10 and a downwardly-directed front portion 11, and the back 10 is provided with a circular opening 12, having an upwardly-directed oblong extension 13, and in practice the collar-button is passed through the circular opening 12 and the shank thereof passes upwardly into the oblong extension 13. The other end of the strap 5 is provided with an ordinary safety-pin 14, and in Fig. 2 I have shown at 15 a part of the lining of a coat, vest, or other garment, and at 16 a section of a collar, a section of a neckband of a shirt being also shown at 17, and the collar 16 and neckband 17 are connected by the usual button 18.

When the fastening device is connected

with the collar-button, as shown and described, the front portion 11 of the hook 9, which projects downwardly over the head of the button 18, serves to hold the necktie, which is passed thereunder, and prevents said necktie from slipping upwardly over the collar.

The safety-pin is connected with the lining of a coat, vest, or other garment, as shown, and securely holds the fastening device and prevents the same from moving upwardly, and it will thus be seen that I accomplish the object of my invention by means of a device which is simple in construction and operation and also comparatively inexpensive.

Having fully described my invention, I claim as new and desire to secure by Letters Patent—

1. A fastening device for the purpose herein described, comprising an elastic strap provided at one end with a safety-pin having a side loop through which one end of the strap is passed, said strap being also provided at the opposite end with a hook, comprising a back and front portion, said back portion being provided centrally with an opening having an extension, and the front portion of said hook being curved downwardly over said opening, substantially as shown and described.

2. A fastening device for the purpose herein described, comprising an elastic strap provided at one end with an attachment whereby it may be connected with the lining of the coat or vest, said attachment being provided with a side loop through which one end of the strap is passed, and said strap being provided at the opposite end with a hook having a loop through which the other end of the strap is passed, said hook comprising a back and a front portion, the back portion being provided with an opening having an extension in a direction opposite to that of the strap, and the front portion being curved downwardly over said opening, substantially as shown and described.

In testimony that I claim the foregoing as my invention I have signed my name, in presence of the subscribing witnesses, this 22d day of October, 1898.

CHARLES A. FEESER.

Witnesses:

JOSEPH C. KENNEDY,
C. T. BEVANS.
